UNITED STATES PATENT OFFICE.

OLIVER T. HUNGERFORD, OF BELLEVILLE, NEW JERSEY.

FIBER-PRODUCING MACHINE.

1,258,336.

Specification of Letters Patent.

Patented Mar. 5, 1918.

Application filed August 9, 1915. Serial No. 44,571.

To all whom it may concern:

Be it known that I, OLIVER T. HUNGERFORD, a citizen of the United States, residing at Belleville, Essex county, and State of New Jersey, have invented and discovered certain new and useful Improvements in Fiber-Producing Machines, of which the following is a specification.

The object of my said invention is to provide a machine for use in removing the "shive" from flax straw and recovering the fiber from said straw, free from said shive and combed out in condition to enable it to be conveniently and successfully used for commercial purposes, such as the manufacture of rope, twine, and other products for which it may be found to be adapted; all as will be hereinafter more fully described and claimed.

20 Referring to the accompanying drawings which are made a part hereof and on which similar reference characters indicate similar parts,

Figure 1 is a top or plan view of the machine embodying my said invention, and

Fig. 2 is a side elevation thereof.

In said drawings the portions marked A represent the main framework of the machine, B the carrier feed table or apron, and

30 C a combing cylinder.

The frame A is of any appropriate construction for the purpose, containing the bearings and other supports for the various parts of the mechanism, and needs no special description except such as may be incidentally required in describing the other parts of the apparatus.

40 The carrier or feed apron B is an endless carrier composed of flexible belts connected by transverse slats and mounted upon wheels 10 and 11, which are mounted on shafts 12 and 13, which are journaled in suitable bearings at the receiving end of the frame A and on the outer end of the table brackets A¹.

45 A pair of longitudinally fluted rolls 14 and 15 are journaled in suitable bearings on the frame A adjacent to the inner end of apron B. Another pair of longitudinally fluted rolls 16 and 17 are positioned adjacent to said pair of rolls 14 and 15, the flutes of the rolls 16 and 17 being finer than those of the rolls 14 and 15. Another pair of rolls 18 and 19 are journaled adjacent to rolls 16 and 17 and are formed with circumferential 55 grooves in their peripheries, the depressions in one roll of said pair registering with the

ribs of the other. Another pair of longitudinally fluted rolls 20 and 21 are positioned adjacent to the rolls 18 and 19, their flutes being of a finer character than those of the rolls 16 and 17.

A shaker cylinder 22 is positioned adjacent to roll 20 and formed with radially projecting teeth at close intervals, covering its entire surface. A pair of rolls 23 and 24 are positioned adjacent to said shaking cylinder 22, and beneath the combing cylinder C is mounted a concave C¹, in which is journaled a series of small rollers 25 at close intervals from end to end of said concave. Each of said rollers 25 has a pinion on its outer end, and an intermediate pinion 26 interposed between adjacent rolls forms a continuous driving connection for said rolls 25 from end to end of the concave. A pulley 27, on the outer end of one of said rolls 25, is connected by belt 28 with a pulley 29 on the corresponding end of roller 23 for transmitting motion to the rolls of said concave. A series of belts, or sprocket chains, 30, 31, 32, 33, 34, and 35 connect pulleys or sprocket wheels on the ends of the shafts of rollers 14, 16, 18, 20, cylinder 22, and roller 23, to establish a continuous drive from the shaft 13 at the inner end of feeding apron B. Another belt or sprocket chain 36 connects the shaft of roller 23 with a sprocket wheel or pulley on the shaft 37 of the combing cylinder C. A driving pulley 38 is mounted on the opposite end of shaft 13 and may be connected by a belt (not shown) with any source of power convenient, or desired.

The combing cylinder C is substantially of the form shown, being armed with six longitudinal rows of spikes or teeth c, positioned equidistant apart around the cylinder and being arranged with their points to operate in close relation with the surfaces of the rollers 25 composing the concave C¹, and with the teeth of each row preferably off-set or "staggered" with relation to the teeth of the adjacent rows.

In operation, the flax straw is thrown upon the feeding apron B, which feeds the same to the first pair of rollers 14 and 15, which serve to crush the straw, breaking the "shive" of the straw into fragments, in which condition the straw is delivered to the next pair of rolls 16 and 17, which, being formed with narrower flutes, serve to still further break up the shive and release it from the fiber of the straw. Said rolls de-

liver the straw to the next pair of rolls 18 and 19, which, being grooved circumferentially, break and crush the straw and shive oppositely from the operation of the other 5 rolls, tending to still further separate the shive from the fiber. Said rolls deliver the straw to the next pair of rolls 20 and 21, which again subject it to a further crushing operation of still more finely fluted rolls and 10 practically reduce the shive to dust or very fine particles. Said rolls 20 and 21 deliver the straw in this condition to the shaking cylinder 22, which not only rotates, but is given longitudinal vibration by reason of a 15 cam connection as shown, and operates to shake the broken shive free from the fiber. Said roll 22 delivers the fiber, practically free from the shive, to the rolls 23 and 24, which flatten out the fiber and deliver it to the 20 combing cylinder C at slow speed. The combing cylinder, running at high speed, operates through the teeth c to comb the fiber and free it from any remaining particles of shive and, at the same time, bring 25 the fibers into horizontal relationship, in which condition they are carried over the concave C¹ by the driven rollers 25, the combing roller C¹ operating, by reason of its speed, to keep the fiber combed straight and 30 deliver it over the outer end of said concave in this condition, practically free from all shive and ready to be converted by any appropriate method into any product for which it may be found desirable.

35 It will be noted that the journal boxes of the rollers 15, 17, 19, 21, and 24 are adjustable by means of screws 40, 41, 42, 43, and 44, whereby the rolls of each pair may be set in relation to each other to accommodate the 40 character of the product to be operated upon.

Having thus fully described my said invention what I claim as new and desire to secure by Letters Patent, is:

1. A machine for recovering the fiber of straw and reducing it to form for the manufacture of fibrous products, comprising a frame, a series of pairs of crushing rolls with fluted surfaces, the flutes of part of 45 said pairs running in one direction and of the others in another direction, a shaking cylinder arranged to receive the straw from said crushing cylinders, feeding rolls adjacent to said shaking cylinder arranged to receive the product therefrom, a combing cylinder 50 arranged adjacent to the opposite sides of said feeding rolls, a concave composed of driven rolls arranged to coöperate with said

combing cylinder, and means for driving said several parts, substantially as set forth.

2. A machine for recovering the fiber of straw and converting it into form for manufacture into fibrous products comprising a frame, a series of pairs of crushing rolls having fluted surfaces, a shaking cylinder arranged to receive the product from said crushing roll, a toothed combing cylinder, a pair of feed rolls interposed between the shaking roll and said feeding cylinder, a concave filled with rolls arranged to coöperate with said combing cylinder, and means for driving said several parts, substantially as set forth.

3. A machine for recovering the fiber of straw and converting it into form for use in the manufacture of fibrous products comprising a frame, a series of pairs of crushing rolls mounted in said frame, means for feeding straw to said crushing rolls, a shaking cylinder for receiving the straw from said crushing rolls, a toothed combing cylinder, rolls arranged in a concave and coöperable with said combing cylinder, a pair of feed rolls interposed between said shaking cylinder and said combing cylinder, said feed rolls being geared to run at a slower speed than the speed of said combing cylinder, and means for driving said several parts, substantially as set forth.

4. A machine for recovering the fiber of straw, comprising a series of pairs of crushing rolls with fluted surfaces, the flutes of some of said rolls running at right angles with the flutes of others of said rolls, a rotatable and reciprocable shaking cylinder arranged to receive the straw from said crushing rolls, a pair of feed rolls arranged to receive the fiber from said shaking cylinder, a toothed combing cylinder arranged to comb out the fiber as it passes through said feed rolls, a concave arranged beneath said combing cylinder and containing a series of rolls coöperating with said cylinder, and a chain of gearing connecting said several parts to the driving mechanism, substantially as set forth.

In witness whereof, I have hereunto set my hand and seal at Belleville, New Jersey, this 5th day of August, A. D. nineteen hundred and fifteen.

OLIVER T. HUNGEFORD. [L. s.]
